4 Claims. (Cl. 112—158)

This invention relates to a pattern stitch sewing machine, particularly to a pattern cam controlling mechanism in such a sewing machine. The object of the invention is to provide a pattern stitch sewing machine equipped with an improved cam controlling mechanism, in which a link mechanism, ratchet wheel mechanism or any other such complicated mechanism is dispensed with and any desired kind of pattern stitches may be readily selected by manually rotating a single dial.

In the accompanying drawing illustrating by way of example an embodiment of the present invention:

FIGURE 1 is a front view of the mechanism according to this invention;

FIGURE 2 shows a plan view thereof partly in section;

FIGURE 3 is a sectional view taken along line III—III of FIG. 2 as seen in the direction of arrow;

FIGURE 3a is an enlarged sectional view of a part of the pattern cams shown in FIGURE 3;

FIGURE 4 is a detail showing the inner face of a selecting dial;

FIGURE 5 shows a diagrammatic development of the circle V shown in FIGURE 4; and

FIGURE 6 shows a diagrammatic development of the circle VI shown in FIGURE 4.

Referring to the drawing, the reference numeral 1 designates a driving shaft having fixed thereto a worm or spiral gear 2, and 3 is an intermediate shaft having an intermediate spiral gear 4 loosely mounted thereon and meshing with said spiral gear 2, the shaft 3 being rigidly mounted in a frame 5 by means of a set screw 6. A cam disc 7 having a gear 7a meshing with a gear formed on one end of the boss of the gear 4 is provided on its upper and lower faces with pattern cams 7b and 7c, respectively. The cam disc 7 is loosely mounted on a stud 8 which is rigidly mounted in the frame 5 by means of a set screw 9. An actuating shaft and contact finger assembly is provided which has upper and lower actuating shafts 10 and 11 axially slidably mounted at their ends in the frame 5, and springs 12 and 12' are wound around said shafts 10 and 11, respectively. Rotatable contact fingers 13 and 14 are mounted on said shafts 10 and 11, respectively, at positions in which they slightly compress said springs 12 and 12'. Spring action of the springs 12 and 12' is taken up by the snap rings 15 and 16, respectively. The ends of the springs 12 and 12' are fixed to the frame 5 and to the contact fingers 13 and 14, respectively, so that said springs 12 and 12' act as biasing means to normally hold the contact fingers out of contact with the cams 7b and 7c, respectively. A counter shaft 17 and a main shaft 18 are rigidly mounted in the frame 5 by means of set screws 19 and 20, respectively. A U-shaped connector 21 is rotatably mounted on the countershaft 17. On the main shaft 18 there is rotatably mounted an intermediate body 22, which is prevented from axial movement by means of snap rings 26 and 27. On the main shaft 18 there is fixed by means of a set screw 25 a link 24, to which is pivoted as at 24a width regulating element 23. The intermediate body 22 has two arms 22a and 22b, and a width controlling arm 28 fixed thereto by means of a screw 29. The arm 22a has an adjusting

screw 22a', and at its free end there is a pin 22a''. An oscillating rod 31 having a pin 30 is associated with a needle bar supporting arm (not shown), and a tension spring 32 connected thereto is secured at its other end to the frame 5. Said tension spring 32 acts upon the oscillating rod 31 so that the width regulating element 23 swings around the pin 24a and the intermediate body 22 swings around the main axis 18 in the counterclockwise direction as seen in FIG. 1. The arm 22a serves to actuate the U-shaped connector 21 so as to press the contact finger 13, and the arm 22b serves to actuate the contact finger 14, so as to bring said contact fingers 13 and 14 into engagement with the pattern cams 7b and 7c, respectively. It is to be understood that the moment of the force urging the fingers 13 and 14 into engagement with the cams 7b and 7c as derived from the tension spring 32 is larger than the moment of the force urging the fingers 13 and 14 out of engagement with said cams 7b and 7c as derived from the springs 12 and 12'. An adjusting screw 33 provided in the frame 5 is for adjusting the amount of movement of the contact fingers 13 and 14. A manually rotatable control member in the form of a dial 34 is rotatably mounted in the frame 5 by means of the stud 35. This dial 34 is provided with three cam portions, viz. a contact finger lifting cam 34a, a contact finger feed cam 34b comprising a plurality of cam faces (a, b, c, . . . i, j, k) as shown in FIG. 5, and another contact finger feed cam 34c comprising a plurality of cam faces (m, no, o, p, q) as shown in FIG. 6. The upper actuating shaft 10 is adapted to engage with the contact finger feed cam 34b, while the lower actuating shaft 11 is adapted to engage with the contact finger feed cam 34c, and the pin 22a'' is adapted to engage with the contact finger shifting cam 34a.

The operation of the mechanism of this invention is as follows:

In the positions of the parts as shown in the drawing, the contact finger 13 is in the position engaging with the cam face A of the pattern cam 7b. Upon the rotation of the driving shaft 1 the cam disc 7 will be rotated through the intermediate gear and, according to the movement of the cam face A, the movement of the contact finger 13 will be transmitted through the U-shaped connector 21, the intermediate body 22, the width making arm 28 and the width adjusting element 23 to the oscillating rod 31, thereby giving an oscillatory movement to the needle bar supporting arm for zigzag motion.

Starting from the above mentioned position, for the purpose of obtaining a desired pattern by the employment of for instance the cam face B, the dial 34 is manually rotated for $2/11\pi$ of a rotation in the direction of the arrow, so as to bring the contact finger 13 into engagement with the cam face B of the pattern cam 7b. (In the example shown, eleven kinds of cam faces A-L are formed on the pattern cam portions 7b and 7c of the cam disc 7.) By such movement of the dial 34, the pin 22a'' will rise along the inclined face of the contact finger shifting cam 34a, thereby actuating the intermediate body 22 and the connector 21, and the contact finger 13 will be disengaged from the cam face A of the pattern cam 7b by the action of the spring 12. During said operation, the upper actuating shaft 10 merely slides on the flat face of the cam face a of the contact finger feed cam 34b, and the contact finger 13 is not displaced axially of the upper shaft 10; the lower actuating shaft 11 will be disengaged from the bottom of the cam face m of the contact finger feed cam 34c and merely moves along the flat face thereof; and said lower actuating shaft 11 will not be displaced axially. When the manual rotation of the dial 34 proceeds and

the pin 22a'' arrives at the top of the contact finger shifting cam 34a, the upper actuating shaft 10 will rise along the inclined face between point *a* and point *b* of the contact finger feed cam 34b, and the contact finger 13 will be transferred from face A to face B of the pattern cam 7b. Upon further rotation of the dial, when it arrives at the angle of rotation of $2/11\pi$ and the pin 22a'' arrives at the top of the contact finger shifting cam 34a, the upper actuating shaft 10 will rise along the inclined face between point *a* and point *b* of the contact finger feed cam 34b, and the contact finger 13 will be transferred from face B toward face A of the pattern cam 7b. Upon still further rotation of the dial, when it arrives at the angle of rotation of $2/11\pi$, the pin 22a'' is lowered toward the bottom of the cam face, whereby the contact finger 13 will come into engagement with face B of the pattern cam 7b due to the action of the tension spring 32; the upper actuating shaft 10 will rest on the flat face of point *b* of the contact finger feed cam 34b, and the lower actuating shaft 11 engages with the bottom of the cam point *n* of the contact finger feed cam 34c. Thus, the movement of the contact finger 13 controlled according to the variation of the cam face of the pattern cam face B will be transmitted to the needle bar supporting arm through the width making rod 31 in a similar manner as to that already described. In this case, the lower actuating shaft 11 is held engaged with the bottom of point *n* of the contact finger feed cam 34c by the action of the spring 12', so that there will not occur any undesirable rotation of the dial 34 caused by slight vibration or shock of the machine. From the foregoing it will be understood that by intermittent rotation of the dial 34 for $2/11\pi$ part of one rotation the point of contact of the control finger 13 and the pattern cam 7b will be shifted in the order B-C-D-E-F.

When the contact finger 13 is in contact with cam face F of the pattern cam 7b, the upper actuating shaft 10 is on the flat face of point f of the contact finger feed cam 34b, and the lower actuating shaft 11 is in loose engagement with the bottom of point r of the contact finger feed cam 34c. Starting from said position, if the dial 34 is manually rotated for $2/11\pi$ part of one rotation in the direction of the arrow, the pin 22a'' will be shifted by means of the contact finger shifting cam 34a; both contact fingers 13 and 14 will be moved away from the pattern cams 7b and 7c; the upper actuating shaft 10 will rise along the inclined face between point f and point g of the contact finger feed cam 34b and will reach the bottom of said point g. At the same time, the lower actuating shaft 11 will be shifted from point r to point s of the contact finger feed cam 34c by the action of the spring 12', and the pin 22a'' will be dropped from the top of the contact finger shifting cam to the bottom thereof by the action of the tension spring 32. Thus, the contact finger 13 will be disengaged from the cam face F of the pattern cam 7b, while the contact finger 14 will be brought in engagement with the cam face G of the pattern cam 7c. Also in this case, any accidental rotation of the dial 34 will be prevented, since the upper actuating shaft 10 is in loose engagement with the bottom of point g of the contact finger feed cam 34b.

While, in the foregoing, the manner of controlling the contact of the contact finger 14 and the pattern cam 7c has been described, it should be understood that the reverse control may be similarly effected.

Taking the example as illustrated, in which eleven kinds of cam faces (A-F and G-L) are formed on the pattern cams 7b and 7c, the relative positions of the contact fingers 13 and 14, the upper and lower actuating shafts 10 and 11, and the contact finger feed cams

34b and 34c may be shown by way of the following table:

		Pattern stitch by—											
5		A	B	C	D	E	F	G	H	J	K	L	
		13	13	13	13	13	13	14	14	14	14	14	
	Contact finger	A	B	C	D	E	F	G	H	J	K	L	
	Pattern cam 7b												
	Pattern cam 7c												
10	Upper actuating shaft	10	10	10	10	10	10	10	10	10	10	10	
	Contract finger feed cam 34b	a	b	c	d	e	f	g	h	i	j	k	
	Lower actuating shaft	11	11	11	11	11	11	11	11	11	11	11	
	Contact finger feed cam 34c	m	n	o	p	q	r	s	t	u	v	w	

From the above table, it will be seen that in case, for example, the pattern stitch according to the cam face C of the pattern cam 7b is to be obtained, the contact finger 13 contacts the cam face C of said pattern cam 7b; the upper shaft 10 contacts point c of the contact finger feed cam 34b; and the lower shaft 11 contacts point o of the contact finger feed cam 34c.

25 While in the foregoing there is described an operation of the device in which the kind of pattern stitch is changed successively by manually rotating the dial 34 intermittently, it is to be understood that according to this invention the said dial 34 may be rotated through two or more pitches, so that the pattern change is effected while omitting any undesired pattern cam face.

What I claim is:

1. In a pattern stitch sewing machine for utilizing a plurality of pattern cams, the combination of a driving shaft, a cam disc having an axis perpendicular to the plane of the disc which axis is also perpendicular to the driving shaft, said cam disc having a plurality of concentric cam patterns on at least one face thereof, an actuating shaft and contact finger assembly mounted adjacent said disc cam and movable in the axial direction of the actuating shaft for moving the contact finger from one cam pattern to another, the contact finger being pivotable about said actuating shaft and engageable with the cam patterns, means biasing said assembly to move said contact finger outwardly of said cam disc, a manually rotatable controlling member in a plane perpendicular to the plane of said cam disc and having a contact finger lifting cam and a contact finger feed cam thereon, the contact finger feed cam being engaged with said assembly for moving said assembly against the action of said biasing means, and contact finger lifting means engaged with said contact finger lifting cam and with said contact finger for lifting said contact finger from engagement with said cam patterns prior to the shifting of said assembly when said manually rotatable controlling member is rotated.

2. In a pattern stitch sewing machine for utilizing a plurality of pattern cams, the combination of a driving shaft, a cam disc having an axis perpendicular to the plane of the disc which axis is also perpendicular to the driving shaft, said cam disc having a plurality of concentric cam patterns on at least one face thereof, an actuating shaft and contact finger assembly mounted adjacent said disc cam and movable in the axial direction of the actuating shaft for moving the contact finger from one cam pattern to another, the contact finger being pivotable about said actuating shaft and engageable with the cam patterns, means biasing said assembly to move said contact finger outwardly of said cam disc, a manually rotatable controlling member in a plane perpendicular to the plane of said cam disc and having a contact finger lifting cam and a contact finger feed cam thereon, the contact finger feed cam being engaged with said assembly for moving said assembly against the action of said biasing means, and contact finger lifting means engaged with said contact finger lifting cam and with said contact finger for lifting said contact finger from engagement with said cam patterns prior to the shifting of said assembly when said manually rotatable controlling member is rotated.

with said cam patterns prior to the shifting of said assembly when said manually rotatable controlling member is rotated, said contact finger lifting means having a contact finger engaging member extending along the path of movement of said contact finger during movement of said assembly.

3. In a pattern stitch sewing machine for utilizing a plurality of pattern cams, the combination of a driving shaft, a cam disc having an axis perpendicular to the plane of the disc which axis is also perpendicular to the driving shaft, said cam disc having a plurality of concentric cam patterns on at least one face thereof, an actuating shaft mounted adjacent said disc cam and movable in the axial direction of the actuating shaft, a contact finger rotatably mounted on said actuating shaft and fixed against movement axially of the actuating shaft, the contact finger being engageable with the cam patterns, spring means engaged with said actuating shaft and contact finger and biasing said actuating shaft and finger outwardly of said cam disc, a manually rotatable controlling member in a plane perpendicular to the plane of the cam disc and having a contact finger lifting cam and a contact finger feed cam thereon, the contact finger feed cam being engaged with said actuating shaft for moving said shaft axially of itself against the action of said spring means, and contact finger lifting means engaged with said contact finger lifting cam and with said contact finger for lifting said contact finger from engagement with said cam patterns prior to the shifting of said assembly when said manually rotatable controlling member is rotated, said contact finger lifting means having a contact finger engaging member extending along the path of movement of said contact finger during movement of said contact finger with said actuating shaft.

4. In a pattern stitch sewing machine for utilizing a plurality of pattern cams, the combination of a driving shaft, a cam disc having an axis perpendicular to the

5 plane of the disc which axis is also perpendicular to the driving shaft, said cam disc having a plurality of concentric cam patterns on both faces thereof, two actuating shafts, one mounted adjacent each face of said disc cam and movable in the axial direction of the actuating shaft, a contact finger rotatably mounted on each of said actuating shafts and fixed against movement axially of the actuating shafts, the respective contact fingers being engageable with the cam patterns on the respective sides of the 10 cam disc on which the actuating shafts are positioned, spring means engaged with each actuating shaft and contact finger and biasing each actuating shaft and finger outwardly of said cam disc, a manually rotatable controlling member in a plane perpendicular to the plane of 15 said cam disc and having a contact finger lifting cam and a contact finger feed cam thereon, the contact finger feed cam being engaged with said actuating shafts for moving said shafts axially of themselves against the action of said spring means, and contact finger lifting means engaged 20 with said contact finger lifting cam and with each of said contact fingers for lifting said contact fingers from engagement with said cam patterns simultaneously prior to the shifting of said assembly when said manually rotatable controlling member is rotated, said contact finger lifting 25 means having contact finger engaging members extending along the paths of movement of said contact fingers during movement of said contact fingers with said actuating shafts.
